CONNECTOR FOR TOY CONSTRUCTION
MEMBERS

Dale W. Adams, St. Francis, Kans.

Application June 17, 1952, Serial No. 293,913

3 Claims. (Cl. 46—29)

1

This invention relates to construction toys, and more particularly, has reference to a connector adapted for joining together a pair of construction members used in the erection of a miniature building or other structure.

Usually, toy construction sets are provided with screws and nuts in substantial quantity, these being used for joining together the several construction members. In this connection, the insertion of screws through registering openings of the construction members, and the application of nuts to the screws after said insertion, is a rather laborious process, and consumes an excessive amount of time.

Accordingly, the main object of the invention is to provide a dog or connector that can be used to separably but firmly join together meeting construction members, merely by insertion of a pin formed on said dog through the registering openings of the members, and swinging of the dog or connector through a relatively short arc.

Another important object is to provide a dog or connector as described that can be used with conventionally designed toy construction members already in use, said members usually being of flat formation and being provided, in each instance, with a longitudinal series of apertures.

Yet another object of importance is to provide a device of the type stated which, after it has been swung to an operative position in which it connects meeting construction members, will be substantially concealed, due to its movement into a position in which it is in full alignment with one of said members.

Yet another object of importance is to provide construction set dog or connector which can be swung to an inoperative, member-disengaging position with maximum speed and ease.

Yet another object of importance is to provide a construction set dog or connector which can be formed at a low cost, and which can be used for a long period of time, due to its rugged construction.

A further important object is to provide a connector so designed as to cause the members joined thereby to be urged into binding engagement with one another, thus to tighten the connection and assure a more sturdy structure.

Summarized briefly, the invention comprises an elongated plate, said plate including a flat body and an extension on one end of the body that is disposed in obtuse relation to the body. The extension is provided with a connecting pin that is extendible through registering apertures of a

2

pair of toy construction members to be joined, the body having a clamp that will engage one of said members when the plate is pivoted about the connecting pin. Due to the angular relation of the extension and body, the members to be joined are urged toward one another during the connecting operation, thus to assure a tighter connection.

Other objects will appear from the following description, the claims appended thereto, and from the annexed drawing, in which like reference characters designate like parts throughout the several views, and wherein:

Figure 1 is a perspective view of a construction set dog or connector formed in accordance with the present invention;

Figure 2 is a fragmentary perspective view of a pair of connected construction members, the dog or connector being illustrated in its operative position;

Figure 3 is an enlarged edge elevational view of the connector, a construction member with which said connector is associated being illustrated fragmentarily;

Figure 4 is a front elevational view, on an enlarged scale, of the connector as it appears when in its inoperative position, the construction members being illustrated fragmentarily and in front elevation;

Figure 5 is a transverse sectional view, on an enlarged scale, taken on line 5—5 of Figure 2; and

Figure 6 is a perspective view of a modified form of connector.

Referring to the drawings in detail, the dog or connector formed in accordance with the present invention has been designated generally by the reference numeral 10, and includes an elongated resilient plate, that comprises a flat, elongated body 12 rigid adjacent one end thereof with a laterally projected handle 14. The plate further includes a flat, relatively short extension 16 on one end of the body, said extension being integral or otherwise made rigid with a laterally projected connecting pin 18. The connecting pin 18 is arranged normally to the plane of the extension 16, and the extension 16 is disposed at an obtuse angle to the plane of the body 12.

As will be noted, the connecting pin projects in a direction opposite from that in which the handle 14 is projected, for a purpose to be made apparent, and it will be further noted that at its free end, the connecting pin 18 is formed with a kerf 20. The kerf 20 has no particular function in the device, except to provide the appear-

ance of a screw head on the end of the connecting pin, thereby to enhance the attractiveness of the completed structure.

Secured to the body 12, intermediate the opposite ends thereof, is a clamp designated generally by the reference numeral 22. The clamp is formed from a single piece of spring metal material, said piece being fixedly connected at one end to one longitudinal edge of the body. Said end of the clamp has been designated by the reference numeral 24, and as will be noted from Figure 5, the end portion 24 is extended in perpendicular relation to the plane of the body 12.

The end portion 24 is integral with an intermediate portion 26, said intermediate portion being disposed obliquely to the plane of the body 12, and merging into a free end portion 28, the free end portion 28 being parallel to the plane of said body.

As will be noted, the piece of material of which the clamp is formed is disposed transversely of the body 12, being fixedly secured at one end to one longitudinal edge of the body and having its other end extended toward but terminating barely short of the other longitudinal edge.

A pair of toy construction members to be joined have been designated 30 and 32 respectively, and it will be understood that these do not, per se, constitute part of the present invention, the illustrated members 30 and 32 being of wholly conventional appearance. Thus, each of the members is formed from an elongated, flat piece of material, having a longitudinal series of apertures. The apertures of the member 30 have been designated 34, and those of the member 32 have been designated 36.

Usually, screws are extended through registering apertures of the members to be joined, but in accordance with the present invention, said screws may be dispensed with. Instead, the members 30 and 32 are so disposed as to register selected apertures thereof, after which the connecting pin 18 is extended through the registering apertures, from the back of one of the members.

At the time the pin 18 is extended through the registering apertures, the body 12 will be disposed in the position thereof illustrated in Figure 4.

Thereafter, the user need only grasp the handle 14, and swing the body 12 in the direction of the arrow shown in Figure 4. This will cause the free end portion 28 of the clamp 22 to extend over the member 32, in the manner shown in Figures 2 and 5. In its final position, the body 12 is disposed in full longitudinal alignment with the member 32, as shown in Figure 2.

Due to the angular relation of the extension 16 and body 12, the extension and body will urge the members 30, 32 respectively toward one another during the operation of connecting said members. As a result, the members will be bound tightly against each other, and when the clamp 22 is in its final position, said members will be firmly joined. After the members have been fully connected, the entire connector or dog will be substantially concealed, since it will be disposed in alignment with and behind the member 32.

In Figure 6, there has been illustrated a modified form, wherein the plate has been designated generally by the reference numeral 38. In this form of the invention, the construction is identical with that of the first form, with the exception that the clamp is extended in an opposite direction. The clamp has been designated 40,

and as will be noted, said clamp is secured to that longitudinal edge of the body opposite from that to which the clamp 22 is secured.

The purpose of the modified construction is to permit the dog or connector to be used in cramped positions in which application of the connector, and swinging of the same to operative position, is difficult.

It is believed apparent that the device is one which can be manufactured at relatively low cost, since it comprises no moving parts and is of simple construction. Further, it is thought to be an important characteristic of the invention that it can be applied to or removed from the members 30 and 32 with maximum speed and ease, in far less time than would be required if a screw were extended through registering apertures of said members, and engaged with a nut.

Still further, it is thought to be of importance that the device is one which harmonizes with the completed structure, and in this connection, it will be understood that the clamp 22 or 40 can be so configured as to blend in with the configuration of the member 32 which it overlies. In this way, the clamp is rendered inconspicuous, thereby increasing the attractiveness of the completed structure.

It is believed apparent that the invention is not necessarily confined to the specific use or uses thereof described above, since it may be utilized for any purpose for which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claims.

What is claimed is:

1. A connector for elongated toy construction members having registrable openings, comprising a resilient plate, said plate including an elongated, flat body and an extension on one end of and arranged at an obtuse angle to the plane of said body; a handle secured to the plate adjacent the other end of the body; a laterally open clamp secured to said body intermediate the ends thereof and proportioned to secure the body face to face with a first toy construction member, said clamp being so arranged upon said body as to align the same longitudinally with said first member in secured relation; and a pin projecting outwardly from the face of said extension on the obtuse angle side in spaced relation to the clamp and extendable through registering apertures of a second toy construction member and said first member to connect the same, the pin forming a pivot about which said plate is swingable into clamping engagement with the first member and said angularly related extension and body being adapted to urge the respective members toward one another, responsive to pivotal movement of said plate into clamping engagement with the first member.

2. A connector for elongated toy construction members having registrable openings, comprising a resilient plate, said plate including an elongated, flat body and a flat extension on one end of and arranged at an obtuse angle to the plane of said body; a handle secured to the plate adjacent the other end of the body; a laterally open clamp secured to said body intermediate the ends thereof and proportioned to secure the

body face to face with a first toy construction member, said clamp being so arranged upon said body as to align the same longitudinally with said first member in secured relation; and a pin normal to the plane of said extension and projecting outwardly from the face of said extension on the obtuse angle side in spaced relation to the clamp, for disposition of the pin through registering apertures of a second toy construction member and said first member to connect the same, the pin forming a pivot about which said plate is swingable into clamping engagement with the first member, and said angularly related extension and body being adapted to urge the respective members toward one another responsive to pivotal movement of the plate into clamping engagement with the first member.

3. A connector for toy elongated construction members having registrable openings, comprising a resilient plate, said plate including an elongated, flat body and a flat extension on one end of and arranged at an obtuse angle to the plane of said body; a handle secured to the body adjacent the other end thereof; a laterally open clamp secured to the body intermediate the ends thereof and proportioned to secure the body face to face with a first toy construction member, said clamp being so arranged upon the body as

to align the same longitudinally with said first member in secured relation, the clamp comprising a piece of spring material secured at one end to one longitudinal edge of said body and extending transversely of the body toward the opposite longitudinal edge thereof; and a pin normal to the plane of said extension and projecting outwardly from the face of said extension on the obtuse angle side in spaced relation to the clamp, for disposition of the pin through registering apertures of a second toy construction member and said first member to connect the same, the pin forming a pivot about which said plate is swingable into clamping engagement with the first member by a user grasping said handle, and said angularly related extension and body being adapted to urge the respective members toward one another, responsive to pivotal movement of the plate into clamping engagement with the first member.
